UNITED STATES PATENT OFFICE.

DESIRE NADEAU, OF COHASSET, MINNESOTA.

COVER-FASTENER.

996,116.

Specification of Letters Patent. Patented June 27, 1911.

Application filed December 8, 1910. Serial No. 596,262.

To all whom it may concern:

Be it known that I, DESIRE NADEAU, a citizen of the United States, residing at Cohasset, in the county of Itasca and State 5 of Minnesota, have invented certain new and useful Improvements in Cover-Fasteners; and I do declare the following to be a full, clear, and exact description of the invention, such as will enable others skilled 10 in the art to which it appertains to make and use the same.

This invention relates to improvements in fasteners or sealing devices for the covers of wooden receptacles.

15 One object of the invention is to provide a fastener or sealing device of this character which will prevent the receptacle from being opened without knowledge of the purchaser.

20 Another object is to provide a cover fastener for wooden buckets or like receptacles, which will be simple, strong, durable and inexpensive in construction, efficient and reliable in operation and which may be quickly 25 and easily applied to the receptacle.

With these and other objects in view, the invention consists of certain novel features of construction, combination and arrangement of parts as will be more fully described and particularly pointed out in the appended claims.

In the accompanying drawings: Figure 1 is a perspective view of a candy pail showing the application of my improved fastening devices. Fig. 2 is an enlarged vertical sectional view through one side of the pail and a portion of the cover showing more clearly the construction and arrangement of the fastener. Fig. 3 is a perspective view of the blank from which the fastener is formed; Fig. 4 is a similar view showing the first step in the construction of the fastener; Fig. 5 is a similar view of the fastener as it appears when ready to be applied to the receptacle; Fig. 6 is a sectional view through one side of the receptacle showing the fastener applied thereto and in the form shown in Fig. 5 or before being bent into engagement with the cover.

50 Referring more particularly to the drawings, 1 denotes my improved cover fastener or sealing device which is preferably formed from a rectangular strip of metal bent or folded upon itself as at 2 to form a doubled 55 receptacle engaging portion 3, the upper end of the inner member of which is bent at

right angles to form a combined supporting lug and nail clenching plate 4 which is adapted to engage the upper edge of the receptacle as clearly shown in Figs. 2 and 6 60 of the drawing.

On the double or folded receptacle engaging portions 3 are formed aligned nail holes 5 through which and through the side of the receptacle is driven an attaching nail 65 6 the inner end of which is clenched into the inner surface of the side of the receptacle as shown. When thus secured to the receptacle the combined lug and nail clenching plate will engage the upper edge of the receptacle 70 as hereinbefore described. When the fastener has thus been secured to the receptacle the cover is applied thereto and rests on the lugs 4 of the fasteners. The projecting upper end of the outer member of the 75 folded receptacle engaging portion projects across the outer edge of the cover and a suitable distance above the same to form a cover fastening lug 7 which is bent inwardly and down into engagement with the upper side 80 of the cover as shown.

In the lug 7 of the fastener is formed a nail hole 8 through which and through the adjacent portion of the cover is driven a fastening nail 9 the inner end of which when 85 driven through the cover comes into engagement with the combined clenching plate and lug 4 which turns the point of the nail back into the inner side of the cover thereby clenching the nail and firmly securing the 90 cover engaging end 7 of the fastener in operative position to securely fasten the cover onto the pail. When the cover is thus fastened it will be obvious that the same cannot be removed without breaking either the 95 cover or the fastening devices thus indicating that the goods contained in the receptacle have been tampered with.

My invention is intended primarily for use in connection with candy transporting 100 receptacles but may be applied to any receptacle formed of wood or similar material, and any number of fasteners may be used for each receptacle.

From the foregoing description taken in 105 connection with the accompanying drawings, the construction and operation of the invention will be readily understood without requiring a more extended explanation.

Various changes in the form, proportion 110 and the minor details of construction may be resorted to without departing from the

principle or sacrificing any of the advantages of the invention as defined in the appended claims.

Having thus described my invention what 5 I claim is:

1. The combination with a receptacle and cover thereof, of a fastening device having a laterally extending lug forming a continuation thereof and adapted to engage 10 with the upper edge of the receptacle upon which the cover bears, means for fastening the plate to the latter below said lug, the opposite end of said plate extending above the cover and adapted to be bent over the 15 edge of the same and upon the upper surface thereof, and fastening nails adapted to be driven through said extended portion of the plate and through the cover, said nails being of sufficient length to be deflected and 20 clenched into the under surface of the cover when driven against the lug.
2. The combination with a receptacle and cover thereof, of a fastening device composed of a single strip of metal folded upon 25 itself at one end, a laterally extending lug

forming a continuation of one end of the plate and disposed between the extremity of the folded portion and the opposite end of the same, said lug being adapted for engagement with the upper edge of the receptacle 30 upon which the cover bears, means for fastening the plate to the side of said receptacle, the opposite end of said strip extending above the cover when attached to the receptacle and adapted to be bent over the 35 edge of the cover and upon the upper surface of the latter, and fastening nails adapted to be driven through said extending and overlapping portion of the plate and through the cover, the said nails being 40 of sufficient length to be deflected and clenched into the under surface of the cover when forced against the lug.

In testimony whereof I have hereunto set my hand in presence of two subscribing witnesses. 45

DESIRE NADEAU.
